UNITED STATES PATENT OFFICE.

HENRY KOHLMYER, OF LORAIN, OHIO.

RAILWAY-TRACK STRUCTURE.

1,085,211.

Specification of Letters Patent.

Patented Jan. 27, 1914.

Application filed October 7, 1911. Serial No. 853,420.

To all whom it may concern:

Be it known that I, HENRY KOHLMYER, a citizen of the United States, residing at Lorain, in the county of Lorain, State of Ohio, have invented certain new and useful Improvements in Railway-Track Structures, of which the following is a specification, reference being had therein, to the accompanying drawing.

10 My invention relates to means for securing railway rails in place, and is in the nature of an improvement over the invention for which Letters Patent No. 993,176 were granted to me May 23, 1911.

15 The object of the present invention is to provide means for securing railway rails to metal ties or other supporting structures having flanges or plates, which shall be simple, cheap and more efficient than the devices heretofore in use.

20 The principle I employ in attaining my object is similar to that embodied in my patented invention, but the clip which I shall hereinafter describe is single, whereas 25 the patented clip is double.

My invention is illustrated in the accompanying drawings in which—

Figure 1 is a transverse section through a rail, showing in side elevation a steel tie and 30 a pair of single clips securing the rail thereto. Figs. 2 and 4 show modified forms of the clip. Fig. 3 is a plan view showing a portion of a rail resting on a tie and secured thereto by clamps such as shown in Fig. 1, 35 said clamps and the adjacent edges of the tie being provided with registering openings or key-ways to receive locking keys. Fig. 5 is a side view of a bar employed for opening and closing the clips.

40 The general arrangement of the track in the present case is substantially the same as in my patent referred to above. The rails are supported on parallel transverse metal ties, and both rails and ties may be of any 45 desired cross section, provided only that suitable flanges are present for the attachment of my clips. The ties shown both in the patented and the present case are I-beams, and the rails have the ordinary T section.

50 For present purposes the essential portion of the tie is its head, having oppositely extending flanges, and it should be understood therefore that requisite conditions would be satisfied by a plate supported for example 55 on a concrete spacing block or base, if said plate were provided with edges capable of

being notched or perforated for the reception of the clip. With this understanding, the following description will be directed to the specific forms shewn.

In Figs. 1 and 3 the rail 1 rests with its foot flange 1^a across the head of the tie 2. Opposite edges of the tie-head are notched at 2^a, to receive the clips or clamping irons 3. The notches 2^a are preferably staggered, 60 that is to say, arranged diagonally on opposite sides of the rail, this being rendered possible by the fact that the clips 3 are single, instead of double as in my patent, where the notches are shown in pairs on the same side

65 of each tie. The clips 3 are formed of heavy stock, which may be malleable steel, capable of being bent by the application of power, but tenacious enough to retain their form under considerable strains. Each clip is 70 formed substantially in U-shape, with a straight back 3^b, grooved out as shown in Fig. 3 to form a key-way. The upper member 3^a may be cut obliquely to permit the insertion of a fish plate, and also to receive the 75 tool shown in Fig. 5, but this is not essential so far as the functions of the clip itself go. The lower member 3^c is straight, and long enough to give a substantial bearing beneath 80 the edge of the tie-head. One side of each 85 notch 2^a is provided with a key-way registering with the notch in the back of the clip when the latter is in place to receive the key or wedge 4, which is driven in tightly to prevent lateral or other accidental displacement 90 of the clip. These key-ways may be either square or round and are preferably though not necessarily, formed with a slight taper.

In Fig. 2 a modified form of clip is shown which can be used in notches in the 95 tie-head, but is specially adapted to be inserted upward through punched or drilled openings surrounded by the metal of the tie. Each of these clips 6 is formed in T-shape, with a heavy head 6^b and a stem 6^a, the latter adapted to be driven or pressed down by means of a clamping tool so as to lock securely over the foot flange of the rail 1. The tool to be used for this purpose forms no part of the present invention, but must be so 100 designed as to exert upward pressure against the head 6^b of the clip coincidently with downward forming pressure on the stem 6^a. The end of the stem is shown cut obliquely as in the clip of Fig. 1, and for the same 110 purposes.

In Fig. 4 a still further modification of

2
the clip is illustrated. In this form, which is designated in its entirety as 7, a head 7^h, and a stem 7^s are provided the same as in the form 6; but the stem carries a spur 7^p, 6 which rests on the upper face of the tie-head, and lends additional stiffness to the stem, in order to resist heavy strains.

The forms of clips shown in Figs. 1, 3 and 4 are preferably made so as to have a driving fit in the notches 2^a, and when driven home and set up, are secured against any accidental displacements. The keys or wedges of Fig. 1 may be adapted to Fig. 4 also if desired by perforating the spur 7^p 15 adjacent to the stem.

In Fig. 5 is shown a bar, which in practice is made about four feet long, of heavy iron or steel, for opening and closing the clips. One end of the bar at 8 is provided with 20 a hook shaped jaw adapted to take under the end 3^a of the clip, so that lifting power applied to the outer end of the bar will spring the clip open. The other end of the bar is provided at 9 with a square hole, made large 25 enough so that it will slip over the clip, to spring the same back to its original form after it has been opened part way by the other end of the bar.

Having thus described my invention, what 30 I claim is:—

1. In a railway structure, a support having a pair of notches through it, a rail having a flange carried on the support between the notches, and two separate masses of malleable metal formed up in the notches so as 35 to forcibly and permanently clamp the support and rail together with auxiliary locking means securing the metal clamps in the notches against lateral displacement.

40 2. In a railway structure, metal tie plates having notches in their opposite edges in pairs, rails laid across said ties with their flanges between the notches of the respective pairs, separate malleable metal clips fitted 45 to the notches and with their upper and lower extremities bent toward each other so as to forcibly clamp the rail and tie plates together, and keys inserted between the notch wall and the clips to lock the latter 50 against shifting.

3. In a railway structure, metal tie plates having notches in their opposite edges in staggered pairs, rails laid across said ties with their flanges between the notches of 55 the respective pairs, and separate malleable

metal clips fitted to the notches and with their upper and lower extremities bent toward each other so as to forcibly clamp the rail and tie plates together, and a headed key having a drive fit between each notch 60 and its clip.

4. In a railway structure, metal tie plates having notches in their opposite edges in pairs, rails laid across said ties with their flanges between the notches of the respective pairs, and separate malleable metal clips fitted to the notches and with their upper and lower extremities bent toward each other so as to forcibly clamp the rail and tie plates together with means engaging each clip and 70 the tie plate to prevent displacement of the clip from the notch.

5. In a railway structure, metal tie plates having notches in their opposite edges in pairs, rails laid across said ties with their flanges between the notches of the respective pairs, and separate malleable metal clips fitted to the notches and with their upper and lower extremities bent toward each other so as to forcibly clamp the rail and tie plates together with keys driven into keyways formed in the opposed faces of the clips and tie plates to prevent displacement 80 of the clips.

6. In a railway structure, a support, a rail 85 resting on the support, and a malleable metal clip having a T head and a stem with beveled tip to form when upset a recess for repair purposes, said stem inserted in an opening in the support and bent over on the 90 rail with a free end bearing on the under side of the support so as to clamp the rail and support together, said T head affording an extended bearing against the support.

7. In a railway structure, a support, a rail 95 resting on the support, and a malleable metal clip having a T head and a stem inserted in an opening in the support and bent over on the rail so as to clamp the rail and support together, said stem having a spur projecting 100 parallel to the T head and adapted to rest on one face of the support while the T head engages the other.

In testimony whereof I affix my signature in presence of two witnesses.

HENRY KOHLMYER.
